EX

DESIGN FOR AN ESCUTCHEON-PLATE FOR DOOR KNOBS AND LOCKS.

SPECIFICATION forming part of Design No. 20,036, dated July 15, 1890.

Application filed June 21, 1890. Serial No. 356,306. Term of patent 7 years.

UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR AN ESCUTCHEON-PLATE FOR DOOR KNOBS AND LOCKS.

SPECIFICATION forming part of Design No. 20,036, dated July 15, 1890.

Application filed June 21, 1890. Serial No. 356,306. Term of patent 7 years.

To all whom it may concern:

Be it known that I, GEORGE S. BARKENTIN, a citizen of the United States, residing at New Britain, in the county of Hartford and State 5 of Connecticut, have invented and produced a new and original Design for Door Knob and Lock Escutcheon-Plates, of which the following is a specification, reference being had to the accompanying photograph, in which the single view fully illustrates my design.

The leading feature of my design consists in the outline and surface ornamentation at the ends of the plate.

A is the main portion or body of the escutcheon-plate, which is in the main a plain surface with the corners for a greater portion of its length beveled or chamfered, as shown. From this plain portion at each end upon one side a bar extends, first longitudinally, 20 and curves inwardly in the form of a scroll a. On the opposite side another ornamental bar extends downwardly and somewhat outwardly, then curving inwardly on a larger circle in the form of a scroll b, which forms 25 the end of the plate and which interlocks or overlaps the smaller scroll, that extends from the opposite corner, as shown. These scrolls are further ornamented by scroll and leaf or-

naments and a dragon-head, which faces the corner of the plate from which the smaller scroll extends. One corner of the scrolls is made in the form of a cove, ornamented by transverse lines, and the scrolls are on an open ground. On the main portion or body of the plate, at each end just inside the scrolls, is a 35 half-leaf-like figure c, formed by a cluster of diverging grooves. The knob should be ornamented in harmony with the rest of the design.

What I claim is—

1. The design for a door knob and lock escutcheon-plate herein shown and described, the same comprising the main portion or body A, with the smaller and larger intertwining scrolls at the ends on an open ground, and 45 leaf-like ornaments, as set forth.

2. In a design for a door knob and lock escutcheon-plate herein shown and described, the end portion having the smaller and larger intertwining scrolls on an open ground, as set 50 forth.

GEORGE S. BARKENTIN.
